BURNER CONTROL

Roy W. Johnson, Milwaukee, Wis.

Application August 12, 1940, Serial No. 352,257

12 Claims. (Cl. 158—28)

This invention relates to an improvement in control mechanism especially designed and adapted for use with heaters of the type wherein the heater is fired by a liquid fuel oil burner.

A typical installation is in connection with a hot air furnace or heater employing a pot type burner, or its equivalent, to which oil or liquid fuel is fed by gravity under control of a metering valve embodied in a constant level oil control device. Air to support combustion is supplied to the combustion chamber usually by means of an electric motor-driven fan.

One of the objects of the invention is to provide a control mechanism of this character, which effectively coordinates the action of the metering valve and of the air supply means so that when the metering valve is fully opened to provide for a high or maximum fire in the burner, air in adequate quantities to support such combustion will be delivered to the fire pot of the burner, whereas when the metering valve is adjusted to cut down the supply of fuel, and lower the flame or fire in the burner, the supply of air will be correspondingly reduced. These advantages obtain irrespective of whether the device is manually or thermostatically controlled.

Another object of the invention is to provide a control device of this character, which may be readily converted from manual to thermostatic control, that is from a structure wherein the control over the metering valve and the interlocked air supply means is regulated by a manually adjustable control knob to one wherein the control over the air and fuel supply is effected by means of a room thermostat, and the arrangement is such that the control exercised by the manually adjustable control knob is available to supplement or refine the control exercised by the room thermostat when the latter is also employed.

Another object of the invention is to provide a control device of this character which automatically shuts off the electric motor driving the fan which supplies the forced draft to the burner when the metering valve is fully closed, and which also automatically brings about movement of the metering valve to pilot or low fire position in the event of current failure.

Another object of the invention is to provide a control device having these advantages and capacities, and which is extremely simple, compact and closely organized in construction, reliable, safe and economical in operation, and easy and comparatively inexpensive to manufacture and install.

Other objects and advantages reside in certain

novel features of the construction, arrangement, and combination of parts, which will be herein-after more fully described and particularly pointed out in the appended claims, reference being had to the accompanying drawings forming a part of this specification, and in which:

Figure 1 is a view in top plan, with the cover plate removed, of an oil and air control mechanism embodying the present invention and of the type which is manually controlled;

Figure 2 is a view in vertical cross section taken on line 2—2 of Figure 1 but showing only the control unit, parts being shown in elevation for the sake of simplicity in illustration;

Figure 3 is a fragmentary view in vertical cross section taken on line 3—3 of Figure 1, parts being again shown in elevation for the sake of illustration;

Figure 4 is a fragmentary view in top plan showing a portion of the cover plate which surrounds the manually adjustable control knob;

Figure 5 is a view similar to Figure 1 but showing the device when converted to a thermostatically controlled unit;

Figure 6 is a fragmentary view in vertical cross section taken on line 6—6 of Figure 5;

Figure 7 is a fragmentary view in vertical cross section taken through the control knob and metering valve and associated elements, parts being shown in elevation for the sake of simplicity in illustration;

Figure 8 is a plan view showing how the oil control device is combined with the damper embodied in the conduit between the motor-driven fan and the combustion space of the burner;

Figure 9 is a view in end elevation of the construction shown in Figure 8; and

Figures 10 and 11 are fragmentary sectional views taken on lines 10—10 and 11—11, respectively of Figure 1.

Referring to the drawings, it will be seen that in both forms of the invention, the control mechanism comprises a main casing, designated generally at 10, and having a main liquid supply chamber 11 therein (see Figures 6 and 7). Liquid fuel is supplied through an inlet 12, equipped with a strainer 13, to an inlet valve 14 controlled in its action by a main float 15 so that a constant level of liquid fuel is maintained in the supply chamber 11. A safety shut-off mechanism, designated generally at 16, is combined with the means for maintaining the level of liquid fuel in the main supply chamber 11, in the manner fully described and claimed in my Patent 2,068,138, granted Jan-

uary 19, 1937, and Patent 2,120,364, granted June 14, 1938.

The liquid flows out of the main supply chamber 11 through an outlet passage 17, which is connected up to the burner (not shown). A tubular valve guide 18 has its lower end press-fitted, or otherwise suitably secured, in the upper end of the outlet passage 17, the valve guide extending vertically in the main casing 10 and terminating a short distance below the upper end of the casing. The valve guide 18 is provided with a lateral opening or port 19 which provides for communication between the interior of the guide and the liquid supply chamber 11. Just below this port the tubular valve guide has an internal valve seat 20. A metering valve 21 is slidably fitted in the tubular valve guide for vertical movement, and has its lower end reduced and slotted and designed to coact with the valve seat 20 and with the internally restricted lower end of the valve guide 18 to meter the flow of oil from the liquid supply chamber 11 to the outlet passage 17. The metering valve 21 also has a beveled portion 22 which snugly engages the beveled valve seat 20 in the fully closed position of the valve so as to completely shut off flow of fuel in such positions. The metering valve 21 is constrained to vertical sliding movement and is held against rotation by means of a transverse guide pin 23 which extends through a diametric opening provided therefor in the metering valve and projects at its ends through and laterally beyond diametrically opposite vertical slots 24 provided in the upper portion of the tubular valve guide 18.

Means is provided for biasing the metering valve to open position and may conveniently take the form of an expansible coil spring 25 having its lower end engaging an abutment 26 and its upper end engaging the under sides of the projecting ends of the guide pin 23.

The control device proper is applied to the top of the main casing 10 and comprises a control casing 27 which includes a floor or bottom wall 28 having integral therewith an upstanding peripheral wall 29 and a depending vertical flange 30 rabbeted around its lower edge to interfit with the upper edge of the peripheral wall of the main casing 10. The control casing is completed by means of a removable cover plate 31 releasably secured in position by a suitable number of screws 32. Screws 32' releasably secure the control casing 27 to the main casing 10.

The portion of the floor 28 on the control casing which immediately overlies the metering valve is provided with an opening having a flange 33 to accommodate the knob-actuated cam means, designated generally at 34, which exercise a manual control over the position of the metering valve. This means includes a control knob proper, designated at 35, which has a skirt 36 depending from the outer peripheral portion of its top and designed to fit over and around the flange 33 in such fashion that the knob may be rotated and also moved vertically or axially with respect to the flange 33.

A variable throw cam 37 is fixed to the lower end of the body portion of the knob 35 by means of a combined abutment and driving plate 38 and screw-threaded stud 39. The details of the construction of this variable throw cam per se form no part of the present invention and are fully disclosed and claimed in U. S. Patent No. 2,244,161, issued June 3, 1941, to Roy W. Johnson. Below its head the stud 39 is provided with a collar 40 which slides in the upper end of the guide 18.

The lower end of the stud 39 bears against a boss 21' formed at the upper end of the metering valve 21. The active face of the cam 37 rides on an abutment lug 41 which may be integrally formed with an adjustable supporting arm 42. The cam is pressed down against the abutment lug by means of a coil spring 43 which encircles the body portion of the knob, abuts the inturned upper edge 33' of the flange 33 at its upper end, and bears down on the combined abutment and driving plate 38 at its lower end.

The supporting arm 42 is constituted of stiffly resilient metal. One end of the arm 42 is fixedly supported on the control casing 27 by means of a rivet 44. The opposite end of the arm is formed with a threaded bearing 45, and an adjusting screw 46 is interthreaded with the bearing 45 and at its upper end has a swivel support in a socket 47 provided therefor in the floor of the control casing. This socket is open at its upper end and the upper end of the screw is cross-slotted to facilitate the turning of the screw and consequent flexure and adjustment of the arm and its abutment. The adjustment thus provided controls the high and low fire positions of the metering valve under the influence of the manually adjustable cam 37.

In order to adapt a manually controlled device of this character to thermostatic control, it is proposed to equip all units at the factory with an auxiliary valve operating mechanism responsive to the control of a room thermostat or other thermo-responsive control means. This auxiliary valve-operating mechanism comprises a valve-operating lever, designated generally at 50, and having one end pivotally mounted or fulcrumed as at 51 on the underside of the casing of the control unit. An arm 52 of the lever is engageable with the guide pin 23 of the metering valve to control the position of the metering valve. The valve-operating lever 50 also has a second lever arm 53, which may be integral therewith and which is preferably horizontally disposed. In fact, as shown in the drawings, the valve-operating lever 50 may be constituted of a sheet metal stamping. The outer end of the arm 53 of the lever 50 engages the lower headed end of an operating pin 54 which is slidably fitted in a bearing 55 integrally formed with the floor of the casing of the control unit. In order to control the high and low fire positions of the valve when it is thermostatically controlled, high and low fire stops for the lever 50 are provided, the high fire stop being in the form of an adjustable screw 56 carried by the floor of the casing of the control unit and engageable with the arm 53 of the lever to limit the upward swing thereof and consequently limit the extent to which the metering valve may move away from its seat. The low fire stop may comprise an adjustable screw 57 threadedly interconnected with the arm 53 of the lever 50 and engageable with the supporting arm 42 to limit the downward swinging movement of the valve-operating lever 50 and consequently the extent to which the lever may move the valve toward its seat.

An electro-responsive power element is provided in the casing of the control unit for controlling the position of the valve-operating lever 50, this power element exerting its control on the valve-operating lever through the sliding pin 54. Preferably the electro-responsive power element comprises generally a bimetallic leaf 60 having one end fixedly supported as at 61 on a terminal board 62 supported within the casing of the con-

trol unit above the floor thereof by means of supporting posts 63 and screw 64. An extension 65, fixed to the free end of the bimetallic leaf, bears on the upper end of the sliding pin 54 in both forms of the invention. An electric heating element 66, encased in mica or other electric insulating material, is supported on the bimetallic leaf in heat interchanging relationship thereto, rivets 67 or the like coacting with its mica casting to secure the electric heating element in position on the bimetallic leaf. The manner in which the energization and deenergization of the electric heating element 66 is controlled and each embodiment of the invention will be hereinafter described.

Referring now to Figures 8 and 9, the numeral 70 designates an electric motor which drives a fan or blower 71. The blast of air from the blower is discharged into a conduit 72, which is coupled up to the burner (not shown). The conduit 72 may be carried in part at least by a bracket 73 fastened to the main casing 10. An opening 74 is provided in the portion of the conduit 72 adjacent the casing 10. A damper 75 is provided for the opening 74 and is fixed to a shaft 76 supported for rotation in bearings 77. A weight 78 fixed to the damper 75 on one side of the shaft 76 biases the damper to a position to close the opening 74. By virtue of its mounting, the damper 75 may be positioned to close the opening 74 or to partially or fully open it, and incidentally, also, when moving away from a position in which the opening 74 is closed to a position in which it is partially or fully open, the damper 75 is effective to block in varying degrees the passage through the conduit 72 from the fan to the burner. One end of the shaft 76 projects beyond the bearing 77 and to this projecting portion of the shaft 76 a crank arm 79 is secured. A crank pin 80 is fixed to the outer end of the crank arm 79 and projects laterally therefrom and is pivotally interconnected at the lower end of the link 81. The upper end of the link 81 is pivotally connected to the outer end of a damper-operating lever, designated at 82, in the form of the invention shown in Figures 1 and 2, and at 83 in the form of the invention shown in Figures 5 and 6. While the damper-operating levers 82 and 83 have one primary function in common, they differ somewhat in construction, and also in their manner of operation, in the two forms of the invention, and hence have been given different reference characters.

Referring now to Figures 1 and 2 it will be seen that the damper-operating lever 82 is disposed transversely of the control unit adjacent the end thereof at which the manually operable knob 35 is located. The damper-operating lever 82 has a straight section 84 with which is integrally formed a curved section 85, the latter extending around the knob 35 and merging into a widened attaching or mounting portion 86, the ends of which are formed with depending lugs 87 (see Fig. 10) having aligned pivot openings which receive the pivot or fulcrum pin 88. This pin is supported on notched seats 89 and is held in position by screws 90 threaded into the control casing and having their heads overlapping and holding the fulcrum pin against its notched seats.

In this form of the invention the position of the damper-operating lever 82 is regulated by the adjustment of the knob 35, but in order that the supply of air from the fan to the combustion chamber may be continued for a short period after the metering valve is closed to insure complete

combustion in or scavenging of the fire pot, the interconnection between the knob 35 and the damper lever 82 is of the special nature now to be described. Underlying the damper-operating lever is an actuating lever 91, which is curved in substantially the same manner as the section 85 of the lever 82, and which has its inner or mounting end widened to a less degree than the widened attaching end of the lever 82, so much so that the widened inner end of the lever 91 is accommodated between one of the lugs 87 and an intermediate bearing lug 87' integral with and depending from the mounting portion 86 of lever 82 and providing an additional bearing for the pin 88 to better adapt the latter to pivotally support the actuating lever 91. The widened inner end of the lever 91 also has upwardly extending mounting lugs 92 which also have aligned pivot openings through which the pivot pin 88 passes to provide a fulcrum for the actuating lever. The driving connection between the knob 35 and the actuating lever 91 is provided by a driving pin 93 fixed in the actuating lever and projecting laterally therefrom so that one end of the pin underlies and is engaged by the lower edge of the skirt 36 of the knob 35. The biasing action of the weight 78 of the damper 75 is sufficiently strong to swing the lever 82 upwardly and cause its driving pin 93 always to engage the lower edge of the skirt 36.

A yieldable interconnection, accommodated in a well 28' formed in the floor of the control casing 21, is provided between the actuating lever 91 and the damper-operating lever 82, and, as shown to advantage in Figure 2, this interconnection comprises a screw 94 having its head countersunk in the damper-operating lever 82, and having its shank extending loosely down through an opening provided therefor in the outer end of the actuating lever 91. A coil spring 95 encircles the shank of the screw 94 below the actuating lever 91 and has its upper end engaged with the lever 91 and its lower end engaged with a nut or collar 96 adjustably mounted on the lower end portion of the screw 94. This yieldable connection tends to cause the damper-operating lever 82 to move with the actuating lever 91, but permits the motion of the lever 82 to lag behind that of the actuating lever 91 under the influence of a dash-pot, designated generally at 97, in certain phases of the operation.

The dash-pot 97 (see Fig. 3) comprises a cylinder 98 having its upper open end formed with an outwardly directed marginal flange, the flanged upper end of the dash-pot abutting a seat provided therefor on the under side of the floor of the casing of the control unit. Screws 99 are threaded into the floor of the control unit and have their edges engaged with the flanged upper end of the cylinder 98 of the dash-pot to firmly secure the cylinder 98 in position. The lower end of the cylinder 98 is provided with an end wall 100 having a central port 101. A disk valve 102 cooperates with the ported end wall at the lower end of the casing 98 and is limited in its movement away from its end wall 100 by means of an internal shoulder 103 formed on the cylinder 98. A piston 104 is slidably fitted in the lower portion of the cylinder 98 which is machined to provide the working chamber of the cylinder. Integral with the piston proper is the tapered extension or stem 105 which is disposed in the portion of the cylinder 98 above the working chamber thereof. A spring 106 encircles the stem 105 of the piston, the spring, at its lower end, bear-

ing on an upwardly facing internal shoulder 107 provided on the cylinder 98 at the upper extremity of its working chamber and having its upper end engaging a collar 108 suitably secured to the upper end of the stem 105 of the piston. The spring is under compression and biases the piston 104 to its uppermost position. The stem 105 and piston 104 are formed with an axial opening terminating short of the lower end of the piston but extending out through the upper end of the stem. A portion of a piston rod 109 is accommodated in this axial opening of the piston. The piston rod 109 has pointed ends, one engaging the tapered formation at the lower end of the axial opening in the piston 104 and the other engaging a tapered recess 110 provided on the under side of the lever 82. When the knob 35 is turned to move the metering valve 21 to fully shut-off position, its skirt 34 moves downwardly as far as it may, and in so doing it presses down on the pin 93 thereby swinging the actuating lever 91 downwardly. This downward motion of the actuating lever tends to cause the lever 82 to swing downwardly with it, but such motion of the lever 82 is resisted by the dash-pot 97, and this with such force that the spring 95 of the yieldable connection between the levers first yields. As the force built up in the spring 95 increases, it gradually becomes sufficient to cause the lever 82, to which it is applied, to move the piston 104 of the dash-pot 97 downwardly, the fit of the piston 104 in the working chamber permitting appropriate leakage between its outer wall and the inner wall of the working chamber of the cylinder 98, the disc valve 102, of course, being closed at the time. Thus, before the damper 75 is moved to full open position, and before the motor switch for the fan is opened in a manner to be hereinafter described, the metering valve 21 is fully closed.

The present invention proposes to incorporate in the circuit for the motor 70 a switch, designated generally at 111, and which is so constituted and so organized with the other elements of the unit that it will automatically close when the metering valve is at No. 1 or higher position, but will be automatically opened by the damper-operating lever 82 shortly after the metering valve has been brought to fully closed or shut-off position. Furthermore, in the same motor circuit the electric heating element 66 for the bimetallic leaf is incorporated so that in the event of current failure, and consequent cessation of the air supply under the influence of the fan 71, the metering valve 21 will automatically be brought to its low or pilot fire position.

For these purposes one side of the line, designated at 112, is connected to binding post 113 mounted on the terminal board 62 and directly connected to the attaching portion 114' of the movable contact 114 of the switch 111. This movable contact 114 is in the form of a blade spring, one end of which is fixed to the binding post 113, as described, and the main portion of which is offset downwardly from the binding post and the underside of the terminal board. The outer extremity of the blade contact 114 is doubled back upon itself, as at 115, and carries a contact button 115' which is engageable with the fixed contact 116 of the switch. The fixed contact 116 of the switch is connected by a flexible and insulated conductor or wire 117 to one terminal of the electric heating element 66. The other terminal of this electric heating element 66 is connected by conductor 120 to one terminal of the

motor 70. The other motor terminal is connected by a conductor 121 to a binding post 122, also mounted on the terminal board 62 and connected by wire 123 to the other side of the line.

The switch 111 is constituted to open and close with a snap action by virtue of the provision of a U-shaped permanent magnet 124, which is carried on a bracket 124' provided therefor. The bracket 124' is mounted on the terminal board 62 and also provides a support for an adjusting screw 116' for the fixed contact 116. The magnet 124 has its poles projecting through an opening provided therefor in the terminal board 62 and straddles the fixed contact 116 in such fashion that when the contact button 115' is proximate to or engaged with its fixed contact 116 it is located in the field of the magnet 124.

In order to provide for the control of the switch from the damper-operating lever 82, this lever is provided with an extension or enlargement 126 having an internally threaded opening therein. A screw 127 is threadedly engaged with this opening and projects below the lever. A strip of insulating material, designated at 128, has one end riveted or otherwise suitably fastened to the body portion of the movable contact 114 and has its outer end underlying and engageable with the lower end of the screw 127. With this construction, when the knob 35 is adjusted to move the metering valve to shut-off or fully closed position, the actuating lever 91 is moved down as far as it may be, and acting through its yieldable connection, and against the action of the dash-pot 97, eventually also moves the damper-operating lever 82 downwardly as far as it may be. As the damper-operating lever 82 approaches the lower limits of its downward swing, the screw 126 strikes the strip 128 and pulls the body of the movable contact 114 downwardly. There is first a certain amount of flexure between the body portion of the movable contact 114 and its double-backed end 115 until sufficient spring energy is stored up to cause the movable contact button 115' to pull away from the fixed contact 116 with a snap action, the spring tension built up having at such time reached a value which is sufficient to overcome the influence of the field of the permanent magnet 124.

When the knob 35 is turned to No. 1 position, or to any position thereabove, then the screw 127 moves up out of engagement with the strip 128, and the switch 111 closes with a snap action under the influence of the inherent tensioning of its movable contact blade 114 and of the permanent magnet 124.

In the form of the invention shown in Figs. 1 and 2, the heating of the bimetal 65, following the closure of switch 111, causes the arm 52 to engage the pin 23 (see Fig. 7) and thus opens the valve to high fire position. Upon closure of the current, the valve will return to the low fire position determined by the setting of the knob 35.

In the form of the invention shown in Figures 5 and 6, the supply of current to the electric heating element 66 is under the control of a room thermostat 130. The fan motor 70 runs continuously and the regulation of the air supply is effected by the damper 76. A screw 131 is mounted on the lever 83 and is releasably held in any adjustment by locking plate 32. The screw depends below the lever 83 and is engageable with the upper surface of the outer end of the strip-like extension 65 of the bimetallic leaf 60. As the high fire position of the metering valve 21 is controlled solely by the bimetallic leaf 60, and as such

a leaf 80 warps slowly upon the deenergization of its heating element 86, there is no necessity for making provision for an overrun by the fan 71, and hence the actuating lever 91 is omitted. The damper lever 83, as well as the metering valve 21, are both controlled from the bimetallic leaf 80, and the switch 111 is omitted. A step-down transformer 133 is provided so that the room thermostat 130, as well as the electric heating element 86, may operate in a low voltage circuit.

The constructions described make readily available either a manually or thermostatically controlled unit which exercises the desired regulation over both the oil and air supply. The units, as to their means for maintaining a constant level, as to the metering valve construction, and as to the auxiliary lever mechanism for operating the metering valve thermostatically, are identical. In both instances the same terminal board is provided and carries a bimetallic leaf and its heating element. The levers 82 and 83 may be interchangeably employed, and when the lever 83 is employed and the device thermostatically controlled, the actuating lever 91, dash-pot 97, and switch 111 may be readily omitted.

Irrespective of whether the device is manually or thermostatically controlled, the bimetallic leaf renders the control mechanism fail-safe. In the event of current failure in either instance, the metering valve is automatically moved to low or pilot fire position. Then, again, when the device is thermostatically controlled, the manually adjustable control knob provides for additional regulation of the low fire position.

While I have shown and described several constructions in which the invention may be advantageously embodied, it is to be understood that the constructions shown have been selected merely for the purpose of illustration or example, and that various changes in the size, shape, and arrangement of the parts may be made without departing from the spirit of the invention or the scope of the subjoined claims.

I claim:

1. A control mechanism for use in regulating the supply of oil and air to an oil burner and comprising a casing having a liquid supply chamber provided with an outlet, a metering valve for regulating flow through said outlet, manually adjustable cam means cooperable with the valve to shift the same from open to closed position and vice versa and thereby vary the amount of fuel supplied to the burner, a fan for supplying air to the burner, a conduit between the fan and burner, a damper in said conduit, a damper-operating lever connected to the damper, an actuating lever having driving connection with and controlled by the adjustable cam means, a yieldable driving connection between the actuating lever and the damper-operating lever, and a dash pot coacting with the damper-operating lever to constrain the same to lag behind the actuating lever upon transmission of opening movement to the damper.

2. In a control mechanism for regulating the supply of oil and air to a burner, a casing providing an oil supply chamber, a metering valve biased toward open position and controlling the flow of oil from the chamber, manually adjustable means limiting the degree of opening of the valve, a fan for supplying air to the burner, a damper controlling the flow of air discharged by the fan and the natural draft to the burner, and delay means including a leverage actuated by the manually adjustable means for stopping the fan

and opening the damper after movement of the manually adjustable means closes the valve.

3. In a control mechanism for regulating the supply of oil and air to a burner, a casing providing an oil supply chamber, a metering valve biased toward open position and controlling the flow of oil from the chamber, manually adjustable means limiting the degree of opening of the valve, a fan for supplying air to the burner, a damper biased toward position to close a natural draft opening and controlling the natural draft and the flow of air discharged by the fan, and delay means including a leverage actuated by the manually adjustable means for stopping the fan and opening the damper upon movement of the manually adjustable means for closing the valve and including an operating lever connected with the damper, a lever for actuating the operating lever, and a yielding connection between the levers whereby movement of one lever may precede movement of the other lever to close the valve before opening of the damper.
4. In a control system for the regulation of oil and air supplied to a burner, a casing providing an oil supply chamber, a metering valve controlling the flow of oil from the chamber, an electric motor driven fan for supplying air to the burner, a switch having its movable contact biased toward closed position controlling the operation of the fan motor, a damper biased toward position to close a natural draft opening and controlling the natural draft and the flow of air to the burner from the fan, a leverage including a lever controlling movement of the switch, a lever actuating the damper and means interconnecting the two levers for delaying movement of the switch until after movement of the damper, and adjustable means connecting the switch with the leverage whereby the damper position is changed before the switch position is changed.

5. In a device for controlling the supply of oil and air to a burner, a casing defining an oil supply chamber, a metering valve controlling the flow of oil from the chamber to the burner, an electric motor driven fan for supplying air to the burner, a switch controlling the circuit of the fan motor and closed by opening the valve, a heat motor including a bi-metallic element and a heater in the circuit to the motor and heated by the flow of current thereto upon closure of the switch, a leverage actuated by the element for closing the valve to low fire position upon failure of current flow to the motor, and means for adjusting the action of the leverage.

6. In a system for controlling the flow of oil and air to a burner, a casing providing an oil supply chamber, a metering valve controlling the flow of oil from the chamber, manually adjustable means for limiting the degree of opening of the valve, an electric motor driven fan for supplying air to the burner, a switch controlling energization of the motor, a damper controlling the flow of air to the burner by natural draft and from the fan, a leverage including a plurality of levers and a yieldable connection therebetween for moving the damper into position to free a natural draft opening upon movement of the manually adjustable means in the direction for closing the valve, means connecting the switch with the leverage for delaying opening of the switch until after opening of the damper, means responsive to flow of current to the motor upon closure of the switch, and means responsive to deenergization of the current responsive means for closing the valve to low fire position.

7. In a system for controlling the flow of oil and air to a burner, a casing providing an oil supply chamber, a metering valve controlling the flow of oil from the chamber, manually adjustable means for limiting the degree of opening of the valve, an electric motor driven fan for supplying air to the burner, a switch controlling energization of the motor, means associated with the valve for closing the switch during the opening of the valve, a damper controlling the flow of air to the burner both by natural draft and from the fan, a leverage for moving the damper into open position for the flow of natural draft upon movement of the manually adjustable means in the direction for closing the valve, an adjustable screw mounted in the leverage and acting on the movable contact of the switch whereby opening of the switch is delayed until after opening of the damper, means responsive to the flow of current to the motor, and means responsive to deenergization of the current responsive means for closing the valve to low fire position.

8. In a system for controlling the flow of oil and air to a burner, a casing providing the oil supply chamber, a metering valve controlling the flow of oil from the chamber, manually adjustable means for limiting the degree of opening of the valve, an electric motor driven fan for supplying air to the burner, a switch controlling energization of the motor, means associated with the valve for closing the switch during the opening of the valve, a damper controlling the flow of air to the burner from the fan and by natural draft, a leverage for moving the damper into open position for the natural draft upon movement of the manually adjustable means in the direction for closing the valve, means connecting the switch with the leverage for delaying opening of the switch until after opening of the damper, a bi-metallic element in the circuit of the motor and heated by the flow of electric current thereto, and a leverage actuated by the element for closing the valve to low fire position upon failure of current flow to the motor.

9. In a system for controlling the flow of oil and air to a burner, a casing providing an oil supply chamber, a metering valve controlling the flow of oil from the chamber, manually adjustable means for determining the degree of opening of the valve, an electric motor driven fan for supplying air to the burner, a switch controlling energization of the motor, a damper controlling the flow of air to the burner both by natural draft and from the fan, a leverage including a plurality of levers and a yieldable connection therebetween for moving the damper into open position for the natural draft upon movement of the manually adjustable means in the direction for opening the valve, an adjustable means mounted in the leverage and acting on the movable contact of the switch whereby opening of the switch is delayed until after opening of the damper, a bi-metallic element in the circuit of the motor and heated by the flow of electric current thereto, and a leverage actuated by the element for closing the valve to low fire position upon current failure to the motor.

10. In a control system for the regulation of oil and air supplied to a burner, a casing providing an oil supply chamber, a metering valve controlling the flow of oil from the chamber, an electric motor-driven fan for supplying air to the burner, a switch having its movable contact biased toward closed position and controlling the operation of the fan motor, a damper biased toward closed position and controlling the flow of air to the burner from the fan and by natural draft, and a leverage including a plurality of levers and a time delay device and a yieldable interconnection therebetween, the leverage connecting the switch and the damper and changing the damper position before the switch position changes whereby fan operation is commenced before the damper is closed to shut off the natural draft and is continued until the damper is opened.

20 11. In a control system for the regulation of oil and air supplied to a burner, a casing providing an oil supply chamber, a metering valve controlling the flow of oil from the chamber, an electric motor-driven fan for supplying air to the burner, a switch controlling the operation of the fan motor, the movable contact of the switch being resiliently mounted, means biasing the movable switch contact toward closed position, a damper biased toward position to shut off natural draft and controlling the flow of air to the burner both by the natural draft and from the fan, a leverage connecting the damper and the switch for changing the position thereof and including a lever controlling movement of the switch, a lever actuating the damper, a dash-pot acting on the damper-actuating lever and a yieldable interconnection between the levers, and adjustable means mounted on the switch controlled lever and bearing on the movable contact mounting of the switch to stress the mounting upon movement of the leverage whereby a natural draft opening is closed by the damper after starting of the fan and is opened before stopping of the fan.

45 12. In a system for controlling the flow of oil and air to a burner, a casing providing an oil supply chamber, a metering valve controlling the flow of oil from the chamber, manually adjustable means for limiting the degree of opening of the valve, an electric motor-driven fan for supplying air to the burner, a switch controlling energization of the motor, a damper controlling the flow of air to the burner from the fan and by natural draft, a leverage for moving the damper into open position for the flow of natural draft upon movement of the manually adjustable means in the direction for closing the valve, means connecting the switch with the leverage for delaying opening of the switch until after opening of the damper for natural draft, means responsive to the flow of current to the motor upon closure of the switch, closure of the switch opening the valve to high fire position, and means responsive to deenergization of the current responsive means for closing the valve to low fire position.

ROY W. JOHNSON.
